(57) **CLAIM**

The ornamental design for a snack container, as shown and described.

DESCRIPTION

FIG. 1 is a front perspective view a snack container showing my new design;

FIG. 2 is a front elevation view thereof, the rear elevation view, left side elevation view, and right side elevation view being identical images thereof;

FIG. 3 is a top plan view thereof;

FIG. 4 is a bottom plan view thereof;

FIG. 5 is an exploded perspective view thereof;

FIG. 6 is a cross-sectional view taken on line 6-6 of FIG. 3; and,

FIG. 7 is a perspective view thereof shown with additional units of the invention shown in dashed lines.

The broken lines shown in the drawings illustrate portions of the snack container that form no part of the claimed design. The broken lines in FIG. 7 showing the snack container in use illustrates environment and forms no part of the claim.
